FIG. 1

FIG. 2

FIG. 3

FIG. 5

FIG. 4

FIG. 6

UNITED STATES PATENT AND TRADEMARK OFFICE
CERTIFICATE OF CORRECTION

PATENT NO. : Des. 480,391 S
DATED : October 7, 2003
INVENTOR(S) : Anthony Dalby et al.

Page 1 of 1

It is certified that error appears in the above-identified patent and that said Letters Patent is hereby corrected as shown below:

Title page,

Item [57], **DESCRIPTION**, the following has been inserted:

-- The broken line showing of the projections extending from the rear of the keymat is for illustrative purposes only and forms no part of the claimed design. The rear of the keymat forms no part of the claimed design. --

Signed and Sealed this

Twenty-second Day of March, 2005

A handwritten signature in black ink, appearing to read "Jon W. Dudas". The signature is written in a cursive style with a large, stylized "J" and "W".

JON W. DUDAS
